HOLDER FOR CUPS

Keith B. Mount, New Providence, N.J., and Clark D. Sims, Huntington Station, N.Y., assignors to Lily-Tulip Cup Corporation, New York, N.Y., a corporation of Delaware

Filed July 25, 1962, Ser. No. 71,052

Term of patent 14 years

(Cl. D44—10)

FIG. 1 is a side elevational view of a holder for cups, showing our new design;

FIG. 2 is an end elevational view;

FIG. 3 is a top plan view;

FIG. 4 is a bottom plan view;

FIG. 5 is a sectional view on line 5—5 of FIG. 1.

The upper portion of a drinking cup is shown in broken lines in FIGS. 1 and 2 for illustrative purposes only.

We claim:

The ornamental design for a holder for cups, substantially as shown and described.
